UNITED STATES PATENT OFFICE.

FRANK A. PICKERNELL, OF NEWARK, NEW JERSEY.

MULTIPLE TELEPHONE SWITCH-BOARD.

SPECIFICATION forming part of Letters Patent No. 463,544, dated November 17, 1891.

Application filed August 17, 1891. Serial No. 402,902. (No model.)

To all whom it may concern:

Be it known that I, FRANK A. PICKERNELL, residing at Newark, in the county of Essex and State of New Jersey, have invented certain Improvements in Multiple Telephone Switch-Boards, of which the following is a specification.

Multiple switch-boards for telephone-exchange central stations are of two general classes, namely: first, those of which the form shown in Letters Patent of the United States No. 305,021, granted September 9, 1884, to Charles E. Scribner, is a type, in which the main circuits pass to the several switch-board sections in successive loops and then to a suitable calling device. On each switch-board section of this class the loop terminals of the several circuits are each provided with a plug-socket or other attachment, including separable spring-contacts, whereby on the insertion of a plug-connector the circuit may be broken, cutting off its normal route through the call-instrument and connecting the outgoing end or ends with a new path or paths through a conductor or conductors (according to whether the circuit is earth-completed or metallic) leading from the said plug to any other such circuit similarly arranged for the purpose of interconnection; second, those of the type illustrated and described in Letters Patent of the United States No. 252,576, granted to Leroy B. Firman, January 17, 1882, in which the main circuits pass to the several switch-board sections by independent normally-discontinuous branches, which are represented on the said sections by terminals in the form of plug-sockets or similar connections of a simple character, in which separable spring-contacts are not required, whereby any two such circuits may be united through any suitable conductor, such as a flexible conducting-cord provided with a plug-connector at both ends.

My present invention relates to multiple switch-boards of the latter class. Switch-boards of this class have heretofore not largely been used, for the reason that when the several main circuits connected therewith have been worked in connection with call-annunciators (they being simply branched to the switch-sections) no simple plan has presented itself whereby the insertion of a con-

necting-plug for the purpose of making connection between two lines has been enabled also to effectuate the breaking of the original route of the circuit through the call-receiving device, which, if unbroken, would ordinarily constitute a shunt or derived circuit to the through talking-circuit, introducing several features decidedly objectionable in practice and materially interfering with the efficient operation of the circuits; such for example as dropping the annunciator of a line wanted, at the answering-switch section of said line in sending a call to the sub-station connected therewith; a partial short-circuiting of the voice-currents through the call device or normal circuit-route of both of two connected lines; and, finally, the reception of a disconnecting-signal not only by the disconnecting-annunciator at the point where any two lines were connected, but also by the original call-indicating devices of both lines concerned, and the consequent misunderstanding which such a multiplication of signals would involve. These difficulties have usually been avoided, where switch-boards of this class have been employed, by adopting the expedient of the Firman patent, to which reference has been made, which is to dispense altogether with a call device included in the working circuits, thus enabling such circuits to remain normally open and to send the calls over a distinct circuit.

The object of my invention is to permit the use of closed circuits and call-annunciators, as usual, avoiding the necessity of extra call-circuits, and at the same time to overcome the difficulties which have been recited.

To this end it consists in employing for the regular signal-receiving annunciators or call-indicators electro-magnets of relatively high resistance and self-induction; and for the disconnecting or "clearing-out" annunciators magnets of relatively low resistance. In thus providing a normal circuit which may remain closed without interfering with the proper operation of the circuits, and in combining these with a multiple switch-board in which the several circuits connected with said switch-board branch to the several switch-board sections.

In the drawings which form a part of this specification, Figure 1 is a diagram indicating

a three-section multiple switch-board, and three metallic circuits branching to each, each of the said circuits being ultimately terminated or having its call-annunciator located at a different section. Fig. 2 is a diagram of two circuits complete, extending each from an exchange-station to a central station, and united at one section of a branching multiple switch-board; and Fig. 3 is a detail diagram of a ringing-key and its connections adapted for use and forming part of my invention.

In Fig. 1, S S² S³ are respectively operating-sections of a telephone central office multiple switch-board M. L, L², and L³ are metallic main telephone circuits, each extending from an exchange or subscriber's station to the said switch-board M, and provided each with an electro-magnetic call device at some one of the operative switch-board sections, so that any two of them may be united by suitable link-conductors at any section. A, at switch-board section S, is the call-annunciator of circuit L. A², at section S², is the annunciator of circuit L², and A³, at section S³, is the annunciator of line L³. Thus the incoming calls of L are received at switch-board section S, those of L² at S², and those of L³ at S³, and it will further appear that whenever a connection is made between any two lines such connection is always at the section at which the call-annunciator of one of the said lines is located, because a call from any circuit for another can only be initiated at the section where the annunciator of the calling-circuit is placed. The circuits shown being metallic, lead through the switch-board to their several annunciators each by conductor l², and then back therefrom by conductor l³. The conductor l² of each circuit has at each switch-board section a terminal or connection attachment s, (in this case a plug-socket) while the other conductor l³ of each circuit has placed in close proximity to its mate a second similar connection or socket s². These connections are united to the circuit-conductors which they represent by short branch wires. Thus circuit L branches to its sockets s and s² on the three sections shown S, S², and S³, respectively, by the several pairs of branches 5 6, 3 4, and 1 2. Circuit L² branches to its terminals by 11 12, 9 10, and 7 8, and circuit L³ branches to its terminals by 17 18, 15 16, and 13 14. These pairs of branch circuits being normally discontinuous, do not interfere with the regular operation in calling of the call-annunciator A. At each switch-board section any required number of interconnection links or appliances N are placed, (but one being shown in the drawings,) which conveniently may be formed of double conductors 19 20, inclosed in a flexible cord provided at its ends with plug-connectors P P², each having two members p p², which are preferably mounted upon a common insulating-handle R. The conductor 20 unites the member p, while the conductor 19 unites members p².

At switch-board section S, lines L and L², are shown as being interconnected for through communication by means of the plugs P and P and their conductors 19 and 20. Instead of arranging the plug-sockets of the several circuits side by side, it is evident that they may be placed one behind the other, in which case in a manner well understood a plug-connector formed with a single member having two conducting-surfaces insulated from each other and in circuit respectively with conductors 19 and 20 would be employed. Bridged across between the link-conductors 19 and 20 of each link appliance N, by means of supplementary conductors 30 and 31, is a disconnecting or clearing-out annunciator d. It will be seen that the two conductors of L and L² constitute when connected, as shown at section S, a through metallic circuit between the exchange-stations X and Y, (indicated by circles and dotted lines in Fig. 1 and more fully in Fig. 2,) that the disconnecting-annunciator d is bridged across the said metallic circuit and is adapted to be operated by and from either sub-station, and that the normal extension-circuits 32 33, through the high-resistance annunciator A, constitutes virtually also a second and third bridge or derived circuit from the points x and y of the main circuits L and L², which are in parallelism with and shunt the extension of each of said main circuits through the other; but I find that by properly constructing and proportioning the electro-magnets of said annunciators their presence and the permanent connection of the parallel circuits in which they are included is rendered perfectly innocuous.

The disconnecting-annunciator d may be constructed as usual with an iron core and tubular case, and I have found a resistance of two hundred ohms to answer well in practice. It is connected in the usual way and is not found to interfere with efficient operation.

The regular main-circuit annunciators A, A², and A³ are wound to a very high resistance. I have experimentally found a resistance as high as sixteen thousand ohms to serve the purpose perfectly, although an annunciator having a resistance as low as three thousand five hundred ohms gives fairly satisfactory results. They are designed to develop a maximum amount of self-induction, and when connected as shown, the two high-resistance and self-induction annunciators A are shunted by the disconnecting-annunciator, the resistance of which is so low as to prevent the former altogether from operating when either sub-station sends the disconnecting-signal, although the said disconnecting-annunciator itself taking the main part of the ringing current is itself perfectly responsive to said signaling operation.

In Fig. 2 two complete metallic telephone-circuits are indicated, extending from exchange or sub stations where they are connected with telephonic apparatus T to a cen-

tral station Z, where both are connected with a multiple switch-board M, which, as hereinbefore described, has at each of its sections S S², &c., branch terminals of all the circuits 5 entering the station, to which terminals the similar terminals of any other circuit may be connected in any desired way. Each circuit is at all times closed at the central station through a regular high-resistance and self-induction annunciator A. At section S the two lines are shown as being connected for conversation by means of double connectors 10 19 and 20 and their terminal plugs, which unite the plug-sockets s and s² of the two lines, and which are themselves united through the bridge-conductors 30 and 31 and the low-resistance annunciator d. The self-induction of the annunciator d is sufficient 15 to prevent it from at all impairing the conversation transmitted between the sub-stations, and since that of the call-annunciator A and A' is much higher than that of d it is clear that these also will not shunt the voice-current, all three, in fact, acting as retardation or choking coils, so far as the conversation-currents are concerned; and I have also 20 found that when in addition to raising the resistance of the regular calling-annunciators in the manner described, the call-generator 25 at the central station is shunted by a resistance equivalent to that of the clearing-out annunciator, as indicated in Fig. 3, during the act of sending an outgoing signal over any circuits to the sub-station called for, the 30 said call can be sent without operating the call-annunciator of said circuit, which may be located at some other section of the switch-board, and which, were it to respond, might be regarded by the operator at such 35 other section as a call-signal. In the figure the circuit L, connecting the telephone appliances T at station X with the call-annunciator A at the central station Z, is shown. Two of the terminal plates s s² of said circuit 40 are shown as being united by conductors 19 and 20 to the two members k and k' of the ringing-key K, which when depressed brings the said members respectively into contact with conducting-plates n and o, which are the 45 terminals of a call-generator V, and at the same time also brings the terminals of said generator into contact with the ends e and f of a resistance r, equivalent to that of the clearing-out annunciator. 50

55 Any of the well-known busy-test systems may be employed in connection with this multiple switch-board arrangement, and although I have described and prefer a switch-board particularly adapted and arranged for metallic circuits, it is evident that my invention is 55 equally applicable to switch-boards in which the main circuits to be manipulated utilize the earth as a return-conductor.

I claim—

65 1. A multiple telephone switch-board comprising main circuits having normally-discontinuous branches leading to connection termi-

nals at its several sections, a relatively-high resistance electro-magnetic call device permanently included in each main circuit at 70 some one of the said sections, means at each switch-board section for electrically uniting any two circuits by connecting their respective branch terminals, and a disconnecting-annunciator of relatively low resistance bridged 75 between the direct and return conductors of any two circuits when so united in a branch circuit shunting the high-resistance call devices of the said circuits.

2. The combination, substantially as hereinbefore described, of two metallic circuits, each permanently closed at a central station through a call-annunciator helix of relatively high resistance and self-induction, a double conductor link connection uniting the direct 85 and return conductors of one of the said circuits with those of the other, and a clearing-out or disconnecting annunciator located in a bridge-conductor between the two conductors of said link connection and serving to 90 shunt the said high-resistance call-annunciators.

3. In a telephone-exchange system, two metallic circuits, each extending from a different sub-station to the same central station 95 and there having their respective direct and return conductors united to constitute a single compound metallic circuit from one of the said sub-stations to the other, in combination with two bridge-conductors, each uniting 100 the direct and return conductors of said compound metallic circuit through an annunciator-helix of relatively high resistance, and a third bridge uniting the said direct and return conductors through an annunciator-helix 105 of relatively low resistance and shunting the said high-resistance helices, substantially as described.

4. The combination, substantially as hereinbefore described, of a closed main telephone-circuit extending from a telephone call-bell at a sub-station to a call-annunciator of relatively high resistance at a central station and connected at said central station by normally-discontinuous branch conductors with connection terminals at each of a series of switch-sections, a link-connection conductor at each switch-section adapted to unite the connection terminals of said main circuit with those of another similar circuit, and a relatively 110 low resistance-disconnecting annunciator included in the circuit thereof, a magnetocall generator for sending outgoing-calls currents to the said sub-station for the operation of said call-bell associated with said link 115 connection, a shunt-resistance substantially equivalent to that of said disconnecting-annunciator, and a ringing-key or equivalent device adapted to connect said generator with the said main circuit and to simultaneously 120 close a shunt-circuit, including the said shunt-resistance between the poles of said generator.

5. In a metallic-circuit multiple switch-

board comprising several operative sections, a series of metallic circuits, each branching to paired connection, terminal sockets located at every section and each looping through a 5 call-annunciator helix of relatively-high resistance and self-induction at some one of the said sections, a double conductor link connection at each section terminating at both ends thereof by plug-connectors having two conducting surfaces or members and adapted 10 to be inserted, respectively, in the said terminal sockets of any two lines and thereupon to unite the said two lines without breaking their normal circuits through their respective call-annunciators, and a disconnecting 15 or clearing-out annunciator having a helix of

relatively-low resistance connected by a cross-conductor from one of the conductors of said link connection to the other and constituting, when the said link connection is connected with any circuit, a shunt-circuit round the high-resistance call-annunciator of such circuit, substantially as and for the purposes specified.

In testimony whereof I have signed my name to this specification, in the presence of two subscribing witnesses, this 8th day of August, A. D. 1891.

FRANK A. PICKERNELL.
